STOCKING

Alfred E. Ischinger, Reading, Pa.

Application April 18, 1950, Serial No. 9,307

Term of patent 14 years

(Cl. D47—7)

To all whom it may concern:

Be it known that I, Alfred E. Ischinger, a citizen of the United States of America, residing at 410 Kenhorst Boulevard, Reading, in the county of Berks and State of Pennsylvania, have invented a new, original, and ornamental Design for a Stocking, of which the following is a specification, reference being had to the accompanying drawing forming part thereof.

The illustration shown in the drawing is a front perspective view of a stocking embodying my new design, the rear of the stocking having the usual appearance of a standard or conventional stocking of modern construction and design.

I claim:
The ornamental design for a stocking, as shown and described.

ALFRED E. ISCHINGER.
